Inventor:

Thomas B. Doolittle

UNITED STATES PATENT OFFICE.

THOMAS B. DOOLITTLE, OF BRIDGEPORT, CONNECTICUT.

SWITCH-BOARD AND CENTRAL-OFFICE APPARATUS.

SPECIFICATION forming part of Letters Patent No. 339,626, dated April 13, 1886.

Application filed November 28, 1885. Serial No. 184,140. (No model.)

To all whom it may concern.

Be it known that I, THOMAS B. DOOLITTLE, residing at Bridgeport, in the county of Fairfield and State of Connecticut, have invented 5 certain Improvements in Switch-Boards and Central-Office Apparatus, of which the following is a specification.

This invention relates to switch-boards and connecting devices for telephonic intercommunication systems.

In a separate case filed on the same day with the present one I have shown, described, and claimed a complete system of intercommunication in which a number of central telephone stations each having converging telephone lines are united by long extramural or trunk lines, so that sub-stations connected with either central station may communicate with those belonging to other central stations.

20 I have in the said separate specification described the general characteristics of the switch-boards at the several central stations. At the principal or terminal stations of a series of trunk lines I provide, in addition to the 25 regular or operating switch-board, at which the trunk lines may be connected with any of the local convergent lines, a testing or terminal-changing switch-board, to which all entering lines are first connected, and from whence 30 they may at the will of the circuit-manager be directed to the annunciators and connecting spring-jacks on the operating board. The lines each terminate in flexible conducting-cords and connecting-plugs, which may be inserted in metallic sockets, these sockets each 35 connecting either by loop or single lines with an annunciator and spring-jack upon the operating switch-board, which is in turn furnished with plugs and cords arranged in pairs for the 40 purpose of uniting any two lines, this being accomplished by inserting the two plugs of any pair of connectors in the respective spring-jacks of the lines to be connected. The necessary devices for sending call-signals and 45 supervising conversations are by suitable switches or circuit-changers adapted to be temporarily included in any of the pairs of cords, and, if desired, in a manner well understood by those skilled in the art, the electro-magnet 50 of an annunciator may be included in the cir-

cuit of each pair to be operated, in order to announce that disconnection is desired. The switch-boards adopted at intermediate central stations are not in the said contemporary case described in detail, but are generally stated to 55 be of a compound order combining themselves measurably, the functions of both testing and operating switch-boards at the principal central stations—that is, the entering lines from every point of the compass, each terminate at 60 the switch-board (where they are readily interchangeable) in a separate and independent conducting cord and plug, while separate pairs of conducting cords and plugs are provided for the interconnections of any two of such 65 lines with one another or with convergent lines.

The present invention embodies the details of the combinations by which these instrumentalities are condensed in a single switch- 70 board.

The object aimed at is to provide more efficient devices for the speedy interchange of lines at an intermediate central station. Assuming that such an intermediate station lies 75 in the route between New York and Boston, and that between those points (each of which is provided with both testing and operating switch-boards) four metallic or double-wire circuits extend. Let it, moreover, be assumed that between the said intermediate station and one of the terminal stations are one or more local single-wire lines. At the two terminal stations are circuit-managers or skilled operatives who connect and cross-connect 80 the several lines as disabilities or circuit faults may render requisite or admissible. At the intermediate stations, however, it frequently occurs that operators or agents of very ordinary acquirements are stationed. These 85 persons are required, at the order of the circuit-managers at the terminal stations, from time to time to make certain similar changes, and it is therefore necessary to provide at such points devices of such simple character 90 as to be readily comprehended, and such as are specially easy and facile of manipulation.

One of the lines of a double-wire circuit 95 may, for example, be out of order between one 100

of the terminal stations and the first intermediate station, and it becomes necessary, to prevent a stoppage of the business, to throw the disabled portion out of circuit altogether 5 and to substitute a perfect wire in the main line between the two said stations. One of the local lines may be temporarily used for this purpose, and the circuit manager at the principal station will first make the change 10 himself and then give the order to the operator at the intermediate station. The lines are in practice all designated with a special number, and are so marked; and it is for the dispatch of business desirable that an order 15 couched in some concise terms—such as “disconnect No. 1 east and connect No. 9 east in its place”—shall be at once understood and instantly complied with.

In accordance with the above this invention 20 consists in embodying in a single electric switch-board connecting cords and plugs placed at one side of the switch-board, each representing a single-line terminal, annunciators and connecting devices each provided 25 with one or more sockets for the reception of the said line-terminal plugs, and a series of pairs of conducting-cords and plug-connectors arranged upon the other side of the switch-board and adapted to be used for connecting 30 any two lines together for connection.

In the drawings which are filed herewith, and which form a portion of this specification, Figure 1 is a vertical cross-section of a switch-board embodying my invention. Fig. 2 shows 35 a portion of a front view of the said switch-board with the paired connecting-cords. Fig. 3 is a drawing of a rear view of a similar switch-board, showing the line terminal cord-conductors, together with the plugs and the 40 plug-sockets constituting the annunciator and plug-jack terminals; and Fig. 4 is a diagram showing the connections of a line-terminal cord, annunciator, plug-jack, and connecting-cord.

In the drawings, A is the table, and B the vertical portion of a switch-board supported upon suitable standards, M. The table or horizontal front board is continued to the rear of the vertical portion by a shelf, C, which is perforated with holes for the line-terminal cords to pass. A series of terminal plugs, *i*, rest by the handle ends upon the shelf C, over the holes, through which the cords *y*, each constituting a single-line terminal, pass. These cords are 55 maintained in place by weights *w*, and are electrically connected with the entering lines 1 2 3 4 5 6, &c., which, as shown, may be brought into the office by means of a cable, D, or in other preferred manner. The ends of the 60 plugs *i* are of metal, and may be formed slightly tapering toward the extremity, or may be screw-threaded, as in the plugs *i*³ and *i*⁴. A series of shelves, *a*, are fixed across the upper or vertical part, B, of the switch-board, 65 and support each a number of combined annunciators and plug-jacks, *b*, each of which

is provided with plug-sockets *s* *s'*, for the insertion of the plug ends *i*. If the tapered plug ends are employed, the holes are merely tapered inwardly and the plugs *i* are inserted 70 and given a half-turn to tighten them; but if the plugs are screw-threaded, as in *i*³ and *i*⁴, the sockets are correspondingly threaded with a female screw, and the plugs can then be screwed therein. 75

Those annunciators which are intended for metallic circuits have both of their circuit terminals attached to the above-described sockets *s* and *s'*, and in Fig. 3 the two lower and the upper rows are so represented, while 80 the second row from the top is assigned to grounded circuits, and is shown as having but the lower socket, *s*, the upper socket being replaced by a binding-screw, *r*, all of the said binding-screws being united by wire and also 85 connected with the ground-wire *j*. The drops or shutters *c* of the annunciators are at the front of the board. Two of the incoming lines, 3 and 4, are shown as being connected with one of the annunciators by their plugs, which 90 are inserted in the two sockets thereof, the weights *w* of the attached cords being thus pulled up, as shown. Line 12, by means of its terminal cord and plug *i*³, is in the same way connected with the grounded annunciator 95 on the third upward shelf.

The first case represents the two wires of a metallic circuit, and the second the single line of a grounded circuit. All of the working lines in like manner are united with some one 100 annunciator, but may with the utmost facility be changed to any other annunciator; or either wire of a metallic circuit it is obvious can readily be withdrawn from any socket and any other given line represented by the 105 proper cord and plug substituted therefor.

The two loops of a metallic circuit, running, for example, east and west, may normally be connected with two separate annunciators—that is to say, the two wires, Nos. 110 1 and 2 east, may be connected with one annunciator, and the two wires Nos. 1 and 2 of the western loop may by means of two separate plugs and cords be connected with another annunciator. 115

When it is desired to connect any two lines or two sections of a through-line together, excluding the annunciator at the way or intermediate office or station altogether, the sockets *h*, which are arranged on the rear edge of 120 the shelves *a*, are used. These are connected together in pairs by permanent connections, and the plugs of the wires to be connected are inserted in the two sockets of a pair, thus giving direct communication without 125 any intermediate electro-magnets; or if the four ends of a metallic circuit are to be so united, these being represented by four adjacent plugs and cords, four sockets will of course be required, *h*¹, *h*², *h*³, and *h*⁴. The two plugs 130 forming the terminals of the two wires from one direction may be inserted into the first

and third or first and fourth sockets, and the two plugs forming the terminals of the two wires from the other direction are then placed in the two remaining sockets.

5 In Fig. 2 a portion of the front of the switch-board is shown, *b* representing the combined annunciator and spring-jack, and *c* the shutter or drop thereof. The cords *z* and *z'* at the front of the board are used exclusively to connect any two of the lines together for communication. They are of two classes—*i.e.*, double conductor for the interconnection of metallic circuits, and single conductor for the interconnection of single-wire lines. The former 15 class is represented by the letter *z'*, and the conducting-cords are terminated by the double conductor-plugs *e*, the cords extending through holes in the table *A*, as already explained in connection with the rear shelf, *C*. The other 20 class is represented by *z*, and each cord ends in a solid plug-connector, *g*. All are connected in pairs, and a pair of single conductor-cords is required to connect two single lines together, which is accomplished by inserting 25 one of the plugs *g* into the spring-jack *t* of one of the lines to be connected and the other plug *g* into the spring-jack *t* of the other line. The metallic circuits are united in the same way.

30 It is not thought necessary to show or describe the various calling and supervising devices in this specification, since they form no part of my present invention.

The spring-jacks and annunciators I employ 35 are preferably combined in one organization, as described in a separate application filed of even date herewith.

In Fig. 4 the relative functions of the two 40 series of conducting-cords are indicated. The letters of reference represent the same parts as in the other figures. The line represented by the cord *y* is connected by the plug *g* with the sockets of the annunciator. This connects by wire 6 with one side of the spring-jack, which 45 normally rests in the case of a metallic circuit jack in contact with a portion of the metallic frame. The frame is united by wire 7 with one wire of the annunciator-magnet *b'*, while the other wire of the said magnet is united by 50 wire 8 with the remaining terminal socket *s*. The plug *g'* of the other main-line cord *y'* is inserted in this socket, thus completing the circuit.

One of the connecting-cords at the front of 55 the board is shown with its plug *e* inserted in the spring-jack *u*, the other plug of the same pair being at rest on the table *A*.

What I claim is—

1. The combination, in a switch-board, of a 60 series of flexible conductors and plug-connectors therefor, constituting line-terminals, with a second series of flexible conducting-cords, provided also with plugs arranged in pairs, the two cords of each pair forming a 65 continuous conductor or pair of conductors, and adapted thereby to act as a connecting-

link between any two circuits, substantially as and for the purposes specified.

2. The combination, in an electric switch-board, of line-terminals comprising flexible 70 conductors and plug-connectors, plug-sockets constituting the terminals of annunciators and adapted to receive the line-terminal plugs, whereby the said annunciators are connected in the line-circuits, spring-jacks, one for each 75 annunciator, included in the circuit of the said annunciator between any two of the said sockets, and a series of pairs of connecting cords and plugs, each pair constituting a continuous conductor with a plug at each end thereof, 80 which plugs are adapted for insertion in the spring-jacks of any two lines, substantially as described.

3. The combination, in an electric switch-board of short station-loops, each including 85 an annunciator and a spring-jack, and terminating in two plug-sockets, one for each end of the said loop, of plug-connectors at the end of flexible cords, each plug constituting the terminal of a line-wire and adapted for insertion in one of the said sockets, and a series of 90 sockets, *h*, united in pairs, also adapted to receive the said plugs, whereby the several line-terminals may be readily connected with any annunciator-loop, with any other line through 95 the said loop, or with any other line direct, substantially as specified.

4. In an electric switch-board, a series of 100 plugs and flexible cords, each forming the terminal of a separate line-wire, a series of pairs of plug-sockets therefor, each pair constituting the terminals of an annunciator, and a 105 separate series of single-plug sockets constituting one terminal of an annunciator, the other terminal of which is attached to a ground-connection, whereby the said line-terminals may be united in pairs to form a metallic circuit through any of the first series of annunciators, or connected to ground through any 110 annunciator, as herein described.

5. An electric switch-board comprising 115 annunciators and spring-jacks, the said annunciators being furnished with terminal sockets at the rear side of the switch-board, the spring-jack orifice opening upon the front side of the same, a series of plug-connectors and flexible conductors, each forming a separate line-wire terminal located at the rear of 120 said switch-board and adapted to unite any of the said line-terminals to any of the said annunciators by means of the terminal sockets thereof, and a series of paired plug-connectors and flexible conductors located at the front of said switch-board, the said plug-connectors being adapted to be inserted in the 125 spring-jack orifices to connect any two of the lines together, substantially as hereinbefore described.

6. An electric switch-board having on each 130 side thereof a separate series of flexible cords and connecting-plugs arranged as described, the plugs and flexible conductors at the rear,

each constituting a single-line terminal, and those at the front side being arranged in pairs for the interconnection of any two circuits, together with annunciators and spring-jacks 5 mounted on the said board and having common terminal sockets, which sockets are adapted to receive any of the line-terminal plugs, the spring-jacks being in like manner adapted to receive the connecting-plugs, substantially 10 as hereinbefore specified, and for the purposes set forth.

In testimony whereof I have signed my name to this specification, in the presence of two subscribing witnesses, this 23d day of November, 1885.

THOMAS B. DOOLITTLE.
